UNITED STATES PATENT OFFICE.

JOHN W. LEES, OF LOS ANGELES, CALIFORNIA.

GRAVER-SHARPENING AND FACET-CUTTING MACHINE.

Application filed August 9, 1926. Serial No. 128,123.

This invention relates to improvements in abrading devices and particularly to that class of abrading devices which are designed for shaping and sharpening gravers and the like and also to devices used by stone cutters in forming facets upon precious stones.

An object of this invention is to provide an improved abrading device having an abrasive element and a work-holder, the work-holder being so constructed that a graver can be mounted thereon so that one of its sides will have a predetermined inclination with respect to the abrasive element, and upon turning the graver over upon its opposite side the opposite side will assume the same inclination with respect to the abrasive element, thus enabling the graver to be equally ground or sharpened upon both sides. In this way it is possible to have the cutting edge on the graver extend perfectly along the center line or longitudinal axis of the graver which is quite essential in many instances where fine engraving is being done.

Another object of this invention is to provide a device wherein a work-holder has a plurality of parallel transverse ridges or projections which are spaced from each other at different distances so that any two of these ridges or projections can be selected between which a graver or other article may be positioned so that the adjustment of the inclination of the side of the graver or other article with respect to the abrasive element can be varied.

A further object of this invention is to provide a work-holder of novel construction which will enable articles to be ground to be easily mounted thereon or removed therefrom.

A still further object of this invention is to provide an abrading device having an abrasive element, a guide bar, and a carriage on the guide bar which is movable thereon, the carriage constituting a work-holder for holding an article to be ground, and to provide arcuate guide bars which can be swung into or out of position and upon which the guide bar is adjustable, so that the inclination of the longitudinal axis of the article to be ground can be varied with respect to the face of the abrasive element.

A still further object of this invention is to provide a device which can be conveniently used either for sharpening gravers or similar articles or for forming facets upon precious stones, wherein the abrasive element

is a rotary wheel. The improved construction when so used is advantageous in that the wear upon the abrasive stone is equally distributed thereover.

With the foregoing and other objects in view which will be made manifest in the following detailed description and specifically pointed out in the appended claims, reference is had to the accompanying drawings for an illustrative embodiment of the invention, wherein:

Fig. 1 is a perspective view of the device illustrated as being employed in sharpening a graver,

Fig. 2 is a similar view to Fig. 1 illustrating another manner in which a graver may be sharpened,

Fig. 3 is a top plan view of the carriage constituting the work-holder,

Fig. 4 is a vertical section taken on the line 4—4 of Fig. 3,

Fig. 5 is a view in end elevation of the work-holder,

Fig. 6 is a vertical section taken on the line 6—6 of Fig. 4,

Fig. 7 is a top plan view illustrating the device as being used in forming a facet upon a precious stone,

Fig. 8 is a front elevation of the same, and

Fig. 9 is a vertical section taken substantially on the line 9—9 of Fig. 8.

Referring to the accompanying drawings wherein similar reference characters designate similar parts throughout, the improved device consists of a supporting panel 10 on which blocks 11, 12 and 13 are mounted. The block 11 extends longitudinally of the panel and is arranged at the back thereof and at the back of a substantially circular aperture 14 formed in the panel. On the top surfaces of the blocks 12 and 13 there are mounted tubular supporting posts 15, the upper ends of which are open. A guide bar 16 is arranged between the blocks 12 and 13 and has nuts 17 threaded onto its ends. These nuts have apertures or bores 18 formed therethrough which receive the posts 15. Set screws 19 are threaded into the ends of the nuts and are engageable upon the posts 15 to hold the guide bar 16 thereon.

A carriage is provided constituting the work-holder, which is slidable upon the guide bar 16 and which is rotatable thereon, the guide bar being circular in cross section. This work-holder or carriage consists of an

elongated block 20 through which the guide bar 16 slidably extends. On the top and bottom surfaces of the block 20 there are fastened small metallic cleats 21 providing ridges or projections on the top and bottom surfaces of the block. These cleats are arranged parallel and extend transversely across the block and are different distances apart for a purpose hereinafter to be described.

An inverted U-shaped member 22 is provided, the top of which is arranged above the top of the block. The parallel arms of the U-shaped member engage the ends of the block and extend downwardly therebelow. The sides of the arms of the U-shaped member are bent toward each other as indicated at 23, and engage upon the sides of the block so that the U-shaped member will be maintained about the block although it is slidable relatively thereto. Apertures 24 are formed in the parallel arms of the U-shaped member 22 through which the upturned ends 25 of a bracket 26 extend. A bowed spring 27 also has its ends extending through the apertures 24, and resting upon the upturned ends 25 of the bracket. The center of the spring 27 engages the bottom of the block 20 or the cleats on the under side thereof, and in this way the U-shaped member 22 would have its top drawn downwardly into clamping engagement against the top of the cleats on the top of the block, so that an article, such as the graver G, may be clamped thereagainst. Bails 28 or equivalent pivoted members are pivoted adjacent the corners of the U-shaped member 22 and are engageable upon the guide rod 16, so that the U-shaped member can be lifted thereby when the bails are pressed toward each other against the action of the spring 27 to facilitate the removal or insertion of the graver.

In Figs. 1 and 2 the abrasive element is shown as consisting of a whetstone W resting upon the supporting panel 10 against the block 11. When the graver is clamped between the block and the U-shaped member and the block is reciprocated upon the guide bar 16, the graver will be ground and sharpened upon the whetstone. Many different types of gravers require that they be sharpened or ground to a line or edge which is exactly parallel to the central longitudinal axis of the graver. In order to accomplish this grinding the cleats are very advantageous. By selecting any two cleats the graver is inserted therebetween, one side of the graver being disposed toward the top of the block. As the graver will engage upon the two cleats it will be held thereby so that its side will assume a certain inclination with respect to the top surface of the whetstone. When this side has been ground by reciprocating the carriage and holding the graver

against the whetstone, the graver is then turned over between these two cleats and the other side will be caused to assume the same inclination with respect to the top surface of the whetstone. In this way both sides of the graver will be sharpened and ground toward an edge which is perfectly parallel to the longitudinal axis of the tool. Various sized gravers may be ground by selecting different pairs of cleats, which, because of their different distances apart, will accommodate these different sizes of gravers.

It is also desirable to vary the inclination of the longitudinal axis of the graver with respect to the top surface of the whetstone. To accomplish this there are provided four apertures 29 in the top of the block 11. Two arcuate guide bars 30 are provided, each having one end rotatably mounted in the outermost apertures 29. In collapsed position the other ends of the arcuate guide bars 30 fit in the apertures adjacent the center of the block 11. These guide bars, however, are capable of being swung from the position shown in Fig. 1 to the position shown in Fig. 2, wherein their swinging ends may be caused to assume positions within the upper ends of the posts 15. In this position on loosening the set screws 19, the nuts 17 can be caused to slide upon the arcuate guide bars, and they can be held in adjusted position by tightening the set screws against the arcuate guide bars 30. In this position it will be appreciated that the longitudinal axis of the graver has a much steeper inclination with respect to the whetstone W than when in the position shown in Fig. 1. When the apparatus is so arranged, the carriage or work-holder can be reciprocated as before to grind or sharpen the graver.

The purpose of having cleats upon both the top and bottom surfaces of the block is to enable a greater variation of inclinations in which it is desired to hold the graver or the article. If those cleats on the top of the block will not provide the desired adjustment, on removal of the bracket 26 and the spring 27, the inverted U-shaped member can be removed from the block and the block turned over and the U-shaped member again applied. In this way the cleats which are shown upon the drawing as being on the under side of the block can be caused to assume the position on the top side of the block against which the graver can be clamped by the inverted U-shaped member.

The improved device can be very advantageously employed in cutting facets upon precious stones, as illustrated in Figs. 7, 8 and 9. When so employed the device is supported upon suitable supports 31 between which a horizontal rotatable grindstone S is rotatable. Such grindstone may be of any preferred construction and is illustrated as being driven by a belt 32 from a motor

33. The grindstone fits in the substantially circular aperture 14 formed in the panel 10. When so used the support or mount 34 which has the precious stone P mounted upon its end is clamped upon the work-holder or carriage, and the work-holder can be caused to slide back and forth along the guide bar 16. If the support or mount 34 is many sided, it can be caused to assume various positions by 10 its engagement with the sides of the cleats and in this way the various facets upon the stone can be properly arranged and cut. By reciprocating the carriage or work-holder back and forth along the guide bar 16, the 15 wear upon the top of the grindstone S will be equally distributed, which is quite advantageous in forming perfect facets. The inclination of the various facets can be varied by swinging forwardly the arcuate 20 guide bars 30 and shifting the guide bar 16 up on to them, so as to vary the elevation of the guide bar 16 with respect to the top surface of the abrasive element.

From the above described construction it 25 will be appreciated that an improved abrading device is provided having many advantages and which may be nicely employed for sharpening gravers or similar implements or for grinding facets upon stones. The improved device serves to hold the article in 30 such a manner that two different sides of the article may be held at the same inclination with respect to the top surface of the abrasive element. It further provides for 35 an adjustment of the inclination of the longitudinal axis of the article with respect to the top surface of the abrasive element.

It will be understood that various changes 40 in the detail of construction may be made without departing from the spirit and scope of the invention as defined by the appended claims.

I claim:

1. A device of the class described comprising an abrasive element, a guide parallel thereto, a work-holder movable upon the guide, means for clamping an article to the work-holder, posts to which the guide means may be connected, means for connecting the guide means to the posts, and pivoted arcuate guide bars adapted to be connected to the posts, said means permitting said guide means to move over said arcuate guide bars as and for the purpose described. 45

2. A device of the class described comprising a support, an abrasive element, a guide bar mounted upon said support, a work-holder comprising a block through which the guide bar slidably extends, an inverted U-shaped member arranged over the block 60 having its parallel arms engaging the ends of the block and portions engageable upon the sides of the block, and spring means urging said U-shaped member into clamping relation against the block. 65

3. A device of the class described comprising a support, an abrasive element, a guide bar mounted upon said support, a work-holder comprising a block through which the guide bar slidably extends, an inverted U-shaped member arranged over the block 70 having its parallel arms engaging the ends of the block and portions engageable upon the sides of the block, spring means urging said U-shaped member into clamping relation 75 against the block, and pivoted members mounted upon the inverted U-shaped member engageable upon the guide bar to force the U-shaped member out of clamping engagement with the block against the action 80 of said spring means.

In testimony whereof I have signed my name to this specification.

JOHN W. LEES.
